SUPPORT FOR TRASH CAN

Edgar L. Dunagan, Lena P. Dunagan, and Kenneth M. Dunagan, Carlsbad, N. Mex.

Application August 31, 1956, Serial No. 607,414

2 Claims. (Cl. 248—346)

This invention relates to a supporting device for a conventional trash can. More particularly, the invention has reference to a device of the character stated that will be adapted to hold a trash can in a properly centered position upon a flat base, so that it will not slide accidentally off the base and so that, further, it will be properly centered if a lid-lifting mechanism such as is shown in Patent No. 2,862,683, issued to us on December 3, 1958, is employed.

One object of importance is to provide a support device for a trash can which will be inexpensively constructed, and will be adapted for engaging a trash can of wholly conventional design and size.

A further object is to form the support device in such a manner that a pair of gripping arms carried by a suitable base may be pivotally swung toward and away from one another, into and out of gripping engagement with the trash can.

Still another object is to so design the support device as to permit the trash can to be slid forwardly out of engagement with the holding arms, whenever it is necessary to empty the trash can or move the same for any other purpose. In this way, lifting of the trash can, which may be quite heavy if fully or substantially filled, is eliminated.

Still another object is to so design the support device for the trash can as to permit the same to be associated with the can without any modification or redesign of the trash can.

Still another object is to so design the device that the swingable arms are adjustable about a common pivot axis, to permit the device to engage trash cans of different sizes.

Other objects will appear from the following description, the claims appended thereto, and from the annexed drawing, in which like reference characters designate like parts throughout the several views, and wherein:

Figure 1 is a perspective view of a trash can support, in which the trash can has been illustrated fragmentarily and in dotted lines;

Figure 2 is a top plan view of the support on an enlarged scale, the gripping arms being shown in full and dotted lines in different positions of adjustment thereof; and

Figure 3 is a sectional view, still further enlarged, on line 3—3 of Figure 2.

Referring to the drawings in detail, the trash can support is adapted to hold a conventional trash can C, and includes a flat base 10 which is of any desired configuration, but which in the illustrated example is of circular configuration with a portion thereof cut away to provide a straight back edge 12.

Medially between opposite ends of the back edge 12, and spaced forwardly a short distance from said back edge, is a vertically disposed pivot bolt 14, the lower portion of which extends through a smooth-walled opening formed in the base 10, said opening being counterbored at its lower end to receive a nut 15 threaded on the lower end of the pivot bolt (see Figure 3).

2

The device includes a pair of arcuate gripping arms 16, 18. Each of these is curved through slightly more than ninety degrees of a circle, and at one end, the arms 16, 18, are formed with alternating, aligned hinge sleeves 20, 22, receiving the pivot bolt 14.

At their outer ends, arms 16, 18 are formed with outwardly rolled lips or flanges receiving bolts 24, 26 respectively. The bolts 24, 26 are disposed in inverted positions, the shanks of the bolts projecting loosely through arcuate slots 27, 27, which slots at the underside of the base having widened portions 28, receiving the heads of the inverted bolts 24.

The slots are curved about the center defined by the hinge pin 14, and are positioned through the rolled sleeves 30, 32 of arms 16, 18. Nuts 34 are threaded upon the upwardly projecting ends of the bolts, and are adapted to bear against the upper ends of the sleeves 30, 32 for the purpose of locking the arms 16, 18 in selected positions to which they are adjusted about the axis of the hinge pin 14.

By reason of the construction illustrated and described, it will be seen that the arms can be swung outwardly to their full line positions of Figure 2, the bolts or pins 24, 26 in these circumstances being disposed at the outer ends of the slots 27. Then, the container C can be positioned in the space between the arms, so as to be embraced by the arms. The arms can be swung inwardly, into gripping engagement with the container, and if desired, the nuts 34 are turned home against the upper ends of the sleeves 30, 32, for the purpose of locking the arms 30 in the selected positions.

It may be noted that the construction permits the arms to be swingably adjusted between opposite extreme positions shown in the full and dotted lines of Figure 2, so as to accommodate the same for gripping containers 35 of different sizes. In all positions to which the arms are adjusted, they will extend beyond a line drawn diametrically of the lower end of the trash can perpendicularly to a second line also drawn diametrically of the bottom of the container and passing through the hinge axis 14 of the arms. In other words, in the full line position of Figure 2, the arms are extended through more than 180 degrees of a circle, and in any other position to which the arms are adjusted, they will still project forwardly a sufficient distance to begin to curve toward each 45 other at their outer ends, thus to insure that the container will be securely gripped and properly centered upon the base 10.

The device has general utility, wherever it is desired to maintain a trash can in a properly centered position upon a base. This prevents accidental pushing of the trash can off the base, and promotes and encourages the proper location of the trash can upon its associated support, each time the trash can is emptied and returned to place.

Further, the device has particular utility when used with a mechanism for lifting the lid of the trash can. Such a mechanism makes it desirable that the trash can be properly centered relative to the lid, and although such a mechanism is not shown in the instant application, a 55 mechanism of this type is illustrated in the above mentioned Patent No. 2,862,683.

It is believed apparent that the invention is not necessarily confined to the specific use or uses thereof described above, since it may be utilized for any purpose to which 60 it may be suited. Nor is the invention to be necessarily limited to the specific construction illustrated and described, since such construction is only intended to be illustrative of the principles, it being considered that the invention comprehends any minor change in construction 65 that may be permitted within the scope of the appended claims.

What is claimed is:

1. A trash can support comprising a flat base; a vertical hinge pin projecting upwardly therefrom; a pair of arcuate arms having inner ends connected to said hinge pin for swinging of the arms toward and away from each other into and out of engagement with a trash can disposed therebetween; and means limiting swinging movement of the arms in opposite directions upon the base, comprising vertical pins to which the arms are connected at their other ends, the base having slots curved about the axis defined by the hinge pin and receiving the last named pins, said other ends of the arms having sleeves integrally formed thereon and loosely receiving the second named pins, said last named pins being threaded, said means further including nuts threaded upon the last named pins to bind the arms against the base in selected positions to which the arms are swung, said slots opening upon the opposite faces of the base, said sleeves at one end contacting one of said faces of the base, said nuts abutting the other ends of the sleeves, the second named pins having heads engaging the opposite face of the base, thus to bind the sleeves against said one face of the base to prevent movement of the arms from selected positions to which they are swung, responsive to threading of the nuts toward the heads of the second named pins, each arm being curved continuously from end to end thereof through substantially 90 degrees, said hinge pin, sleeves, and last named pins all being disposed wholly exteriorly of the arcs defined by the respective arms.

2. A trash can support comprising a flat base, a vertical hinge pin projecting upwardly therefrom; a pair of arcuate arms having inner ends connected to said hinge pin for swinging of the arms toward and away from each other into and out of engagement with a trash can disposed therebetween; and means limiting swinging movement of the arms in opposite directions upon the base, comprising vertical pins to which the arms are connected at their other ends, the base having slots curved about

the axis defined by the hinge pin and receiving the last named pins, said other ends of the arms having sleeves integrally formed thereon and loosely receiving the second named pins, said last named pins being threaded, said means further including nuts threaded upon the last named pins to bind the arms against the base in selected positions to which the arms are swung, said slots opening upon the opposite faces of the base, said sleeves at one end contacting one of said faces of the base, said nuts abutting the other ends of the sleeves, the second named pins having heads engaging the opposite face of the base, thus to bind the sleeves against said one face of the base to prevent movement of the arms from selected positions to which they are swung, responsive to threading of the nuts toward the heads of the second named pins, each arm being curved continuously from end to end thereof through substantially 90 degrees, said hinge pin, sleeves, and last named pins all being disposed wholly exteriorly of the arcs defined by the respective arms, said base having downwardly opening recesses formed in its underside, said recesses communicating with the slots over the full length of the slots and being wider than the slots, the heads of the last named pins being disposed wholly within said recesses and extending over substantially the full width of the recesses.
